FILLING METHOD AND APPARATUS

John C. Goshorn, Baltimore, Md.

Application April 30, 1934, Serial No. 723,185

3 Claims. (Cl. 226—72)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to an improved method and apparatus for filling containers, with loose granular or powdered material. The invention is herein described in connection with the filling of gas mask canisters which contain granular chemicals, but obviously the invention is not so limited, since it may be used in filling any type of container.

In the canisters used for filtering air passing to gas masks, it is essential that the granular chemical filtering material be packed uniformly and tightly into the canister to provide the maximum quantity of material and to prevent channeling of the material during handling and storage. If the filtering material is not compactly packed into the canister, channels will form in the material due to handling of the canister, thus affording inadequate filtering of the air.

Furthermore, gas mask canisters usually have an inner receptacle which may be perforated or 25 permeable in which the granular material is placed, this inner receptacle positioned in and spaced from the walls of an outer casing. An inner tube extends into the granular material and the gas mask hose is connected to the open end 30 of this tube. In filling the canisters with the granular material, it is essential that this material does not lodge in the inner tube nor in the annular space between the inner and outer receptacles.

An object of this invention is to provide a simple and accurate method and apparatus for completely filling and packing to a maximum density loose material into a container.

Another object of this invention is to provide 40 an improved method and apparatus for rapidly filling and packing loose material into a container without spilling any of the material.

Another object of this invention is to provide 45 an improved device for filling and packing granular or other loose material into a container to a definite level.

With these and other objects in view which will 50 be apparent from the following description and claims, this invention consists in the parts and combinations herein described and claimed, with the understanding that the several necessary elements of the invention may be varied in construction, proportions, and arrangement without departing from the spirit of the invention nor exceeding the scope of the appended claims.

In the drawing,

Fig. 1 is a sectional view of the filtering element of a gas mask canister ready to be filled, with my improved filling device in position.

Fig. 2 is a top view of the filling device.

Fig. 3 is a sectional view of another form of filtering element for gas mask, with a slightly modified filling device.

Fig. 4 is a top view of the filling device of Fig. 3.

Referring to Figs. 1 and 2, there is shown a 10 porous cylinder 1 which is adapted to contain granular material such as impregnated charcoal for purifying air drawn therethrough. The cylinder 1 may be made of felt or of several layers of filter paper wrapped on a perforated metal 15 cylinder (not shown), or it may be made of paper pulp formed into shape and dried. The cylinder 1 is adapted to be positioned within an outer container, the construction being generally similar to that shown in U. S. Patent No. 1,501,286 granted July 15, 1924, to Frank A. Logan.

The cylinder 1 has a cover 2 secured over one end and having an opening in which is secured a flanged nipple 3 to the inner flange of which is secured an air outlet conduit 4. Outlet conduit 4 is preferably a thin perforated metal tube which extends beyond the center line of cylinder 1. Conduit 4 may be covered with a fine mesh cotton or other fabric sleeve to prevent the granular chemical material from entering conduit 4.

The parts thus far described are assembled, leaving one end of cylinder 1 open. Into this open end is placed the filling device 5 consisting of a cylinder adapted to telescope a short distance into cylinder 1. The filling device 5 has 35 a bottom wall 6 having its lower surface perpendicular to the longitudinal axis of the device 5 and having its upper surface at an angle thereto and slanting downwardly to an opening 7. A shoulder 8 is adapted to rest on the upper edge 40 of cylinder 1 in order that the filling device may be inserted a predetermined distance into cylinder 1, since the bottom 6 determines the level to which cylinder 1 is filled.

The granular chemical filling for the gas mask 45 filter is placed in the filling device 5 and the cylinder 1 is then jiggled rapidly to cause the material to pass through opening 7 into cylinder 1 and to compact the loose material. The material completely fills the cylinder 1 to the bottom 50 wall 6 and packs against this bottom so tightly that channeling of the material will not occur even when the container is shaken violently and dropped.

The jiggling may be vertical or horizontal or a 55

combination of vertical and horizontal. Excellent results have been obtained by vertical jigging, a simple form of apparatus for this purpose being shown. A cradle 9 having suitable recesses to accommodate the nipple 3 and the lower walls of cylinder 1 has secured thereto an arm 11 to which is secured a strap 12 on an eccentric 13. Upon rotation of eccentric 13 the cradle 9 and the cylinder 1 and filling device 5 are 10 jigged vertically.

The operation is as follows. An empty cylinder 1 is placed in cradle 9 and the filling device 5 is positioned as shown. The granular chemical filling is then dumped into device 5, preferably 15 slightly more than the quantity required to completely fill the cylinder 1, and jigging is started by rotation of eccentric 13. The loose material passes through opening 7 to the cylinder and packs firmly and uniformly against the bottom 6.

20 When the cylinder 1 is full there will remain some loose material in the filling device 5. One of the objects of this invention is to prevent this excess material from spilling around the machine or into parts of the canister where it is undesirable. The filling device 5 is therefore tilted away 25 from the opening 7 as it is removed, thereby causing the excess material to be retained on the bottom 6.

It will be apparent that the bottom wall 6 of 30 the filling device functions as a top to determine the level of the loose material and against which the material tightly packs, and as a shelf or closed pocket upon which excess material may be positioned to prevent spilling.

35 After removal of filling device 5, a permanent top is put on cylinder 1, the top preferably being forced down to further compact the granular material.

The form of the invention shown in Figs. 3 40 and 4 is slightly modified for use with a different type of gas mask filter. This form of gas mask filter 15 is cylindrical and has a unitary closed bottom and a top 16 secured thereto. A flanged nipple 3 and outlet conduit 4 are secured to the top 16, these parts being similar to those of Fig. 1. The cover 16 is set down into cylinder 15 a short distance and is secured to and supports the nipple 3 and conduit 4.

Cover 16 has an opening 17 near one side of 50 cylinder 15. The filling device 18 has a bottom wall 19 having an opening 20 for alignment with opening 17, and an upwardly projecting cylindrical cap 21 which is adapted to telescope over nipple 3 and close the open end thereof. Cylinder 15 fits into a cradle 22 connected at its lower end to bar 23 having a strap 24 around eccentric 25. The bottom 19 is progressively thicker away from opening 20, as in the form shown in Fig. 1.

The operation of this form of invention is 60 similar to that of Figs. 1 and 2. The filler 18 is removed by tilting away from opening 20, causing the excess material to gravitate away from the opening. The excess material is thus pre-

vented from entering the outlet conduit 4 or falling out of the filling device 18.

It has been found that loose material packed in accordance with this invention is more compact, and more of the material may be packed 5 in a container than by prior methods of filling and tamping.

In some instances, it has been found desirable to arrange the container and filling device at an angle to the vertical during filling. When this 10 is done, the eccentric opening of the filling device is positioned slightly higher than the opposite side, it being found that with some jigging movements the material may be more firmly packed against the bottom of the filler when this angular 15 arrangement is used.

It will be understood that this invention is not limited to the specific jigging mechanism shown, nor to the filling of gas mask filters.

While I have shown and described the preferred embodiments of the present invention, I wish it to be clearly understood that I do not confine myself to the precise details of construction herein set forth by way of illustration, as it is apparent that many changes and variations 25 may be made therein by those skilled in the art without departing from the spirit of the invention or exceeding the scope of the appended claims.

I claim:

30

1. As a new article of manufacture, a filling device for filling containers with loose material comprising a tubular member open at its top, with a bottom wall substantially closing the lower end and having an opening of substantially less area 35 than that of the closed portion of the bottom, said opening being positioned eccentrically with respect to the bottom, the lower face of the bottom being at right angles to the longitudinal axis of the tubular member and the upper face thereof 40 sloping progressively downwardly toward the opening.

2. As a new article of manufacture, a filling device for use with a container having an open end and adapted to be filled to a definite level 45 with loose solid material, said filling device comprising a tubular member open at its top, with a bottom wall substantially closing the lower end thereof and having an eccentrically positioned opening of substantially less area than that of 50 the bottom wall; said filling device being adapted to be telescoped into the open end of the container whereby the bottom wall thereof determines the level of filling, and means to jig the container and filling device whereby the loose material is packed firmly against the bottom of the filling device.

3. The invention as defined in claim 2, characterized in that the upper face of the bottom wall of said filling device slopes progressively 60 downward toward the opening therein.

JOHN C. GOSHORN.
